UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

SUPPORTING DEVICE.

Application filed February 9, 1923. Serial No. 618,022.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Sup-
porting Devices, of which the following is a
specification.

My invention relates to supporting devices
0 and has particular reference to a device for
supporting trolley conductors from an over-
head structure although it is applicable to
other uses.

The object of my invention is to produce
5 a device in which the parts supported may
be alined with respect to the support, and
also there may be yielding relative move-
ment between the parts supported and the
support. Other objects will appear as I
0 proceed with a description of my invention
in detail.

In the drawing accompanying this specifi-
cation and forming a part thereof:

Fig. 1 is a side view of a device in partial
5 section embodying my invention and the de-
vice shown is particularly adapted to the
supporting of a trolley wire clamp with re-
spect to an overhead support.

Fig. 2 is a sectional view taken on the line
0 2-2 of Fig. 1 and shows a positive limit-
ed relative rotation of the parts for alining
purposes.

Fig. 3 is a partial sectional view of Fig.
1 showing the relative axial movement of
5 certain parts.

Fig. 4 is a partial sectional view of Fig.
1 showing relative movement of certain
parts, said movement differing from that of
Fig. 3.

0 Fig. 5 is a modification of my invention
showing a device embodying my invention
and capable of attachment and detachment
to an insulated or other form of support.

In the preferred form of device embody-
5 ing my invention I employ a body member 1
provided with a cavity 2 and diametrically
opposite projecting arms 3, each provided
with a U shaped hook 4 to receive an over-
head span wire as is well known in the art
0 and in common use. Other forms of sup-
port may be substituted for the arms 3, all
of which are well known at the present day.

Within the cavity 2 is electrical insulating

material 5 which is usually applied under
heat and extreme pressure. Embodied in
the insulation is a supporting mechanism 6.
This supporting member comprises the body
member 7 with a projecting flange 8 which
anchors the supporting mechanism within
the insulating material 5. The body mem-
ber 7 is provided with a cavity 9 having in-
tegrally formed therewith at one side a lug
10. Rotatably mounted in the cavity 9 is
a supporting member 11, and secured within
the cavity by means of the turned over flange
12. The flange 12 is preferably cast straight
as shown by the dotted lines in Fig. 1 and
after the member 11 has been properly po-
sitioned the flange 12 is turned inwardly, as
shown by the full lines in Fig. 1, by rolling,
stamping or other suitable means. The sup-
porting member 11 is shown furnished with
projecting means 13 screw threaded to re-
ceive a trolley wire clamp of any of the nu-
merous forms now in use. Projecting from
the supporting member 11 is a lug 14 which
is adapted to engage with the lug 10. As
shown, the member 11 being rotatable, the
lug 14 will engage with the member 10 on
either side thereof, limiting the amount of
rotation of the member 11 with respect to
the body member 1. In order to normally
maintain the member 11 in position against
the flange 12 and to permit relative, vertical
or axial movement of the member 11 with
respect to the body member 1 along the
axis $\alpha-\alpha$, I insert a spring 15 between the
face 16 and the supporting member 11.

The object of this axial movement of the
supporting member 11 with respect to the
body member 1 is to permit an upwardly,
vertical yielding movement of the trolley
wire due to an upward pressure upon the
trolley wire by the current collector. This
axial movement of the member 11 with re-
spect to the body member 1 is found of great
advantage in eliminating what is commonly
known in the art as "hard spots," that is, it
is found that wherever the trolley wire is
supported, either through the medium of a
span wire or rigid overhead support, that at
such points of support there is a decided
blow given to the trolley wire which in
time has a detrimental effect upon the trol-
ley wire at this point, and the object of my
invention is to add to the point of support

a yielding or flexible movement, thereby eliminating, or reducing to a large degree at least, the so-called "hard spot."

Another function of my invention is to permit the trolley wire and its clamp to pivot or yield due to the approach of the trolley collector toward the ear and its retreat therefrom. It will be evident that when the current collector approaches and retreats from the trolley clamp that the upward pressure thereof will tend to cause the trolley clamp to pivot about its support, and if the trolley clamp is rigid and will not pivot, then there is a relative movement of the trolley wire with respect to the clamp which in time has a crystallizing effect upon the wire, and causes the same to break and also causes considerable wear upon the wire adjacent the ends of the clamp. It will be noted in Fig. 4 that there is a pivotal action possible between the supporting member 11 and the body member 7 and since the construction of the member 11 is circular and uniform, and the same is true of the flange 12, the member 11 is free to pivot with respect to the flange 12 at any point about the circumference of the member 11. This pivotal action is also brought about against the pressure of the spring 15.

In the description just given the supporting mechanism involving my invention and the hanger member 1 are incorporated in a single unit and insulated with respect to each other, but it is possible to so modify the construction that the device embodying my invention may form a detachable part of an insulated hanger to be secured to any form of support, and such a modification is shown in Fig. 5 and has the advantage of being capable of attachment to any of the standard hangers in general use.

A standard form of hanger is represented as H, having a threaded stud 20 embedded therein. Secured to the stud is shown a supporting mechanism 21 embodying my invention, and which comprises a body member 22 interiorly threaded to receive the stud 20 and provided with a flange 23. Mounted upon the flange 23 is a supporting member 24 provided with a projecting threaded member 25 to which may be secured a trolley wire clamp. The supporting member 24 is provided with a cavity 26 and to the interior wall of the member 24 is secured a lug 27 adapted to engage a lug 28 integrally secured to the flange 23 of the body member 22. The members 22 and 24 are rotatable relative to each other, but the amount of rotation in either direction is limited by the lugs 27 and 28. The member 24 is mounted on the member 22 by means of the flange 29 which, like the flange 12, is preferably cast straight as shown by the dotted lines and then formed inwardly. A spring 30 interposed between the parts 22 and 24 holds

the parts extended to their limit, but permits the part 24 to yield upwardly along the axis y—y under an upward pressure of the trolley collector when passing the point of support the same as the construction herebefore described.

The construction will also permit a pivotal motion of the member 24 with respect to the member 22 in any direction about the circumference of the member 23.

It will be observed that the operation of the modified device embodying my invention shown in Fig. 5 performs all the functions of the device shown in Fig. 1, but is of such a construction that it can be applied to practically any form of support now on the market. In fact, if additional movement is desired to that permitted by the construction shown in Fig. 1, the device shown in Fig. 5 can be attached to the threaded stud 13 of Fig. 1, thereby increasing the amount of relative movement of the parts.

In the use of the device herein described and shown in Fig. 1, the same is first attached to an overhead span supporting wire which supporting wire usually crosses the trolley wire at right angles thereto, but may cross it at varying angles.

The trolley clamp or ear which is attached directly to the trolley wire is then placed in position with respect to the stud 13 and rotated in the proper direction until the boss of the ear engages with the lower face 17 of the supporting member 11. The rotation of the clamp or ear is continued in which case the member 11 will also rotate in the same direction until the lug 14 engages with the lug 10. This engagement prevents the further rotation of the member 11, but permits the forcing of the clamp or ear into tight engagement with the face 17 of the member 11. The clamp or ear may now be in alinement to receive the trolley wire, or it may not, and if the latter is the case, then the trolley clamp or ear may be rotated in a reverse direction in which case the member 11 will also rotate, permitting the alinement of the clamp or ear with the trolley wire.

The clamp or ear having been installed upon the wire, it is now free to pivot or move vertically with respect to the body member 1 as shown in Figs. 3 and 4. As the current collector, pressing upwardly upon the trolley wire, approaches the clamp or ear, the inclination is for the clamp or ear to pivot upwardly as shown in Fig. 4 and when the trolley collector is directly below the center of the device or in line with the axis x—x the tendency is for the clamp or ear to move upwardly as shown in Fig. 3. As the current collector retreats from the clamp the tendency is for the clamp or ear to pivot in the opposite direction.

The description of the use of the construction shown in Fig. 1 applies equally well to that in Fig. 5. The device is first attached to the stud 20 and the trolley clamp or ear is then secured to the stud 25 and rotated until the lug 27 engages with the lug 28 in which case continued rotation of the trolley clamp or ear will tend to move all parts in the same direction thereby tightening the member 22 against the lower face of the hanger H and tightening likewise the clamp or ear against the lower face of the member 24. If now the trolley clamp is not in alinement with the trolley wire, the clamp is rotated in the reverse direction, together with the member 24, until alinement does take place.

Where a new construction is being installed, the device shown in Fig. 1 may be used, but in an old construction my invention can be applied thereto by merely removing the trolley clamp and inserting between the clamp and the hanger the device shown in Fig. 5.

There are many modifications no doubt which will be apparent to those skilled in the art, but which will embody my invention and therefore, I do not wish to be limited other than by my claims.

I claim:

1. An article of manufacture comprising a body member provided with means to secure the body to a support, a cavity within said body member, electrical insulation embedded within the cavity, and a supporting mechanism embedded in the insulation, but electrically separated from the body member, the supporting mechanism comprising a member provided with means to secure it within the insulation and provided with a cavity, a member rotatably mounted in the cavity and having supporting means projecting therefrom, and a resilient member interposed between the rotatable member and the interior wall of the cavity to maintain the rotatable member in yielding relation to the other parts as and for the purpose described.

2. An article of manufacture comprising a body member provided with means to secure the body to a support, a cavity within said body member, electrical insulation embedded within the cavity, and a supporting mechanism embedded in the insulation, but electrically separated from the body member, the supporting mechanism comprising a member provided with means to secure it within the insulation and provided with a cavity, a member rotatably mounted in the cavity and having supporting means projecting therefrom, means to limit the amount of rotation of the rotatable member and a resilient member interposed between the rotatable member and the interior wall of the cavity to maintain the

rotatable member in yielding relation to the other parts as and for the purpose described.

3. An article of manufacture comprising a body member provided with means to secure the body to a support, a cavity within said body member, electrical insulation embedded within the cavity, and a supporting mechanism embedded in the insulation, but electrically separated from the body member, the supporting mechanism comprising a member provided with means to secure it within the insulation and provided with a cavity, a member rotatably mounted in the cavity and having supporting means projecting therefrom, means to limit the amount of rotation of the rotatable member in both directions and a resilient member interposed between the rotatable member and the interior wall of the cavity to maintain the rotatable member in yielding relation to the other parts as and for the purpose described.

4. An article of manufacture comprising a body member, means to secure the body to a support, a cavity within said body member, electrical insulation secured within the cavity and a supporting mechanism secured in the insulation but electrically separated thereby from the body member, the supporting mechanism comprising a member provided with means to secure it within the insulation and also provided with a cavity, a rotatable member having a limited rotation in either direction mounted within the cavity, means to secure an article to be supported to the rotatable member and a resilient member engaging the rotatable member to maintain the rotatable member in yielding relation to the other parts as and for the purpose described.

5. An article of manufacture comprising a pair of electrically separated members, electrical insulation interposed therebetween, means to secure the article to a support, one of the members provided with a freely movable and rotatable member secured thereto, means to limit the amount of relative rotation, resilient means interposed between the rotatable member and its supporting member to permit a free yielding relation between the movable and rotatable member and its supporting member as and for the purpose described.

6. An article of manufacture comprising a pair of electrically insulated members forming a unit in which the members are held in a fixed relation, means on one member to secure the unit to a support, supporting means rotatably secured to the other member, and means to limit the rotation of the supporting means relative to its supporting member.

7. An article of manufacture comprising a pair of electrically insulated members forming a rigid unit, means to secure the

unit to a support, supporting means yieldably secured to said unit to yield axially with respect to said unit and resilient means to yieldingly resist said movement of the 5 supporting member.

8. An article of manufacture comprising a pair of electrically insulated members forming a rigid unit, means to secure the unit to a support, supporting means pivotally secured to the unit and means to yieldingly resist said pivotal movement.

9. An article of manufacture comprising a pair of electrically insulated members forming a rigid unit, means to secure the unit to 15 a support, supporting means provided with a circular member mounted to pivot relative to the unit about any point around the edge of the circular member, and means to yieldingly resist said pivotal movement in 20 any direction.

10. An article of manufacture comprising a pair of electrically insulated members forming a unit, means to secure the unit to a support, a supporting member mounted 25 to rotate freely at all times within limits, and means establishing said limits.

11. An article of manufacture comprising a hanger, a supporting member secured thereto, means preventing movement of the 30 supporting member and hanger in a direction away from each other, means permitting relative movement of the hanger and supporting member in a direction towards each other and means yieldingly resisting 35 the latter movement of the supporting member.

12. A supporting device for a conductor support comprising a body member, means to secure the device to a support, a supporting member secured to the body member and having means for attachment to the conductor support and having universal movement 40 relative to the body member and means to yieldingly maintain the parts in a predetermined relation.

13. A supporting device for a conductor support comprising a body member, means to secure the device to a support, a supporting member secured to the body member and

having means for attachment to a conductor support and having a universal and a rotative movement relative to the body member and means to limit the rotative movement to a predetermined amount.

14. A supporting device for a conductor 55 support comprising two inter-engaged members rotatable relative to each other, means on one member to secure the device to a support and means on the other member to secure a conductor support thereto and 60 means to limit the relative rotation of the members in both directions.

15. A supporting device for a conductor support comprising two interengaged members movable axially relative to each other, 65 means on one member to secure the device to a support and means on the other member to secure a conductor support thereto, means to yieldingly resist relative movement of the members in one direction when subjected 70 to impact or pressure in said direction.

16. A hanger comprising a body member, a supporting member secured to the body member in electrically insulated relation thereto but having a limited relative rotation with respect to the body member, means forming a part of the supporting member to attach a conductor support to the supporting member by rotation, and means to prevent the rotation of the supporting member in one direction while securing the conductor support thereto and permit a simultaneous reverse rotation of the conductor support and supporting member.

17. A hanger provided with a support 85 therefor and having in combination a supporting member to receive a conductor support, the supporting member having a limited relative rotative movement with respect to the hanger, means to limit the relative rotation of the supporting means in 90 both directions with respect to the hanger and permitting a relative and simultaneous rotation of the supporting member and the conductor support between the aforesaid 95 limits.

In testimony whereof I affix my signature.
SAMUEL S. MATTHES.
